Primary Examiner — Jennifer L Watkins(74) *Attorney, Agent, or Firm* — Pearne & Gordon LLP(57) **CLAIM**

The ornamental design for an orthosis, as shown and described.

DESCRIPTION

FIG. 1 is a front perspective view of a first orthosis showing my new design;

FIG. 2 is a rear view thereof;

FIG. 3 is a front view thereof;

FIG. 4 is a left side view thereof;

FIG. 5 is a right side view thereof;

FIG. 6 is a front perspective view of a second orthosis showing my new design;

FIG. 7 is a rear view thereof;

FIG. 8 is a front view thereof;

FIG. 9 is a left side view thereof; and,

FIG. 10 is a right side view thereof.

The broken lines shown in the drawings depict environment and form no part of the claimed design.

1 Claim, 10 Drawing Sheets(56)
